UNITED STATES PATENT OFFICE.

CHARLES L. MCCUEN, OF EVANSTON, ILLINOIS, ASSIGNOR, BY MESNE ASSIGNMENTS,
TO DELCO-LIGHT COMPANY, OF DAYTON, OHIO, A CORPORATION OF DELAWARE.

REFRIGERATING MACHINE.

Application filed November 1, 1919. Serial No. 335,081.

The invention relates to improvements in refrigerating apparatus, and particularly to refrigerating apparatus of the compression type, and while the invention is shown applied to refrigerating apparatus of the compression type commonly used by householders, butchers, grocers, bakers and the like, it will be apparent that the invention may be applied to a much wider field and to cover practically all conditions where refrigeration is desirable, due regard being had by the designer or adapter of the various parts of the mechanism of the invention to meet the specific conditions under which it is desired 15 to use the same.

The primary object of the invention is to generally improve the design, construction and arrangement of the various parts or units making up a refrigerating apparatus 20 of the compression type, and in the embodiment of the invention herein shown and described, such apparatus is designed so as to be of a compact form that may be conveniently attached to, and supported upon 25 the casing and within the refrigerating compartment of refrigerators of the described character and of a conventional design.

It is another object of the invention to provide an improved system for automatic electric control of refrigerating apparatus of the described character.

It is a further object of the invention to provide certain improvements in the design and allocation of the various units of the 35 machine, rendering the same more compact and slightly in appearance than heretofore attained in machines of this character.

The invention relates to a refrigerating machine of the water cooled type, and it is 40 one of the objects of the invention to improve the water circulatory system, the same being under the control of the means which operates the compressor ordinarily used for compressing and circulating the refrigerant, 45 preferably sulphur dioxide, (SO_2).

It is another object of the invention to improve in a refrigerating machine of the described character the construction and arrangement of the condensing and compressing chambers and mechanism connected therewith, whereby the parts requiring adjustment and cleaning are made easily accessible, and particularly with respect to the water circulatory system when it is desired 55 to use the invention in localities in which

the available water supply is not pure and injurious deposits or accumulations of foreign materials may require frequent cleaning.

In the use of refrigerants of a highly volatile character as sulphur dioxide (SO_2) it is highly important that the refrigerant be in a permanently closed circulatory system and the invention provides a novel construction of condensing apparatus in which the water system including the cooling surfaces of the condensing coils may be thoroughly cleaned without disturbing or opening the circulatory system for the refrigerant.

Other objects of the invention will appear 70 from the following description which is directed to the preferred embodiment of the invention depicted also in the drawings forming a part of the specification.

In the said drawings, Fig. 1 is a diagrammatic view of the apparatus with parts of the improved units thereof shown in section to disclose certain details of construction.

Fig. 2 is an enlarged sectional view taken through the compression chamber and 80 through the condenser chamber with certain parts of said chambers in section, and showing also a modified form of the base of the condenser.

Fig. 3 is a horizontal view partly in section on line 3—3 of Fig. 2 looking downwardly.

Fig. 4 is a detailed view of the test cocks, Fig. 5 a top plan view of the water pressure controlled electric system, etc., and Fig. 6 a 90 section on the line 6—6 of Fig. 5.

In the embodiment of the invention as illustrated in the drawings a base for supporting the compressor chamber and the usual electric motor is shown, being designated by the reference character a , b indicating the motor, and the wall of the compressor chamber being designated generally by the reference character c . The base a may conveniently be mounted upon the top of 95 an ordinary refrigerator of the household type. 10 is a continuation of the motor shaft designed to drive a suitable rotary pump enclosed within a housing or casing j , which is designed preferably for detachable 100 connection with the wall of the compressor chamber c passing through an opening provided therein so that the operative portions of the pump mechanism within the casing 105 will extend on the interior of the compres- 110

sor casing as illustrated in Figs. 1, 2 and 3, whereby the same may be normally immersed in an oil bath as illustrated in Fig. 1, the top level of the oil being indicated by the reference character 12, and may be controlled or determined by suitable try cocks or by plugs as indicated by reference characters 15 and 16 communicating with and closing the openings 13 and 14.

Upon the top wall of the compressor chamber *c*, which wall consists of a specially formed closure plate indicated by the reference character *k*, I mount a condenser chamber, the walls of which are indicated by reference character *d*.

The machine of the type herein disclosed employs a refrigerating fluid contained in a closed circuit with which the pump casing *j* and the compressor casing *c* are connected in series, the pump discharging into the compressor casing. The fluid which I prefer to use is sulphur dioxide (SO₂). *e* is an expansion coil designed as common with this class of machines for insertion within the refrigerating chamber of a householder's refrigerator. *f* indicates an expansion valve interposed in the system between the condenser chamber and the expansion coil. *g* designates a water cooled liquid refrigerating fluid reservoir or receiver for the liquefied refrigerant also interposed in the system between the compression chamber and the expansion valve *f*. Reference character *h* designates generally what I call a scale trap in the system, the same being in the return pipe and interposed between the expansion coil and the compressor.

The pump *j* is preferably of the rotary type comprising two intermeshing gears having a liquid seal, one of which gears is directly connected with the shaft 10, such pump being preferably of the type fully described in prior patents, Reissue No. 14,112 of April 18, 1916 to Leonard et al., and 1,233,069 of July 10, 1917 to G. I. Leonard. This pump is secured to the wall of the compressor *c* and completely submerged on the inside of the compressor casing below the oil level 12 as described, there being one or more inlet ports 17 through which the lubricating oil or other suitable sealing fluid will enter the pump casing by suction created therein where in a well known manner it will form a gas or liquid seal resulting in the formation of a vacuum within the pump casing when the shaft 10 is operated to cause the separation of the intermeshing teeth of the gears. 18 is the inlet port (Fig. 3) for the refrigerant and connected therewith by a hand controlled valved connection 19 is the tubular passage pipe 20 completing the connection between the scale trap *h* and the pump, there being a check valve 21 interposed in this pipe to guard against backward currents or flow of refrigerant from

the pump toward the scale trap. 22 is a pressure gauge in pipe 20, the intake end of the latter being positioned near the bottom of the trap and being cut off from the intake part of the trap, which communicates through pipe 23 with expansion coil *e* through the vaporizer or slug tank *m*, by a screen 24 through which the refrigerant must pass and which screen will be of suitable construction to prevent the entry of any scale or foreign solid particles into the pump mechanism.

The construction and mode of operation of the pump is such as to produce when in operation a vacuum in its suction chamber and at the same time to expel the oil or sealing fluid therefrom through the vertical tube 25 which has its outlet above the normal level of the sealing fluid in the pump chamber. 26 is a saucer-shaped plate or baffle mounted on the underside of the top wall *k* of the pump casing, being held in position by one or more screws 31 entering lugs 27 by which it is spaced from the lower surface of the top wall to permit of the refrigerant, when under compression within the pump chamber, to pass through the central opening therein in the manner indicated by the arrows, Fig. 1, and through the vertical central tube 28, the opening in plate *k* being designated by reference character 29. Suitable connection between vertical tube 28 and the opening 29 may be made by screw threading the parts as indicated (Figs. 1 and 2) and the upper end of the tube 28 is screw threaded and takes the double clamping nut 30, which is utilized also to form a gas tight pipe connection with the fitting 32. The fitting 32 has a vertically extending portion having a hollow interior or passage 33 normally closed at its upper extremity by a needle valve 34. There is a laterally extending branch of the fitting 32 having a passage 34' therein serving as a header and which has a plurality of openings 35 with which the four coiled tubes 36 connect. The upper extremity of the fitting 32 is screw threaded and provided with a valve seat to accommodate the needle valve 34, which is screw threaded in the enlarged opening 34' therein above the valve seat. On this screw threaded upper end of fitting 32 there are suitable clamping nuts between which the casing *d* of the condensing chamber is locked in position and a liquid tight joint is secured between the fitting and the casing. 37 is the locking nut on the underside of the top plate of casing *d* and 38 is a washer or gasket encircling the threaded upper extremity of the fitting 32 and being held in position by the clamping nut 39, also screw threaded on the upper extremity of the stem of fitting 32, and cap 40 covers the exposed end of the screw threaded needle valve 34. Cap 40 may also be utilized as a lock for nut 39 in

effectively clamping the parts together. The needle valve 34 is made up of a pointed shank with an enlarged portion at its upper extremity, as shown in Fig. 2, and provided 5 with an angular upper extremity designed to take a tool by which the needle may be backed off the seat to permit any entrapped air to escape from the system in filling the refrigerating system initially or in adding 10 refrigerant thereto at any subsequent time.

The reference character 41 indicates one of a plurality of suitable supporting frames provided with a foot which is secured by screw 42 to the plate *k* at the lower end of 15 the condenser chamber and the coils 36 may be held in this rectangular supporting frame by suitable spreaders 43 vertically arranged between the cylindrical coils. The coils 36 after passing through a number of convolutions terminate at their lower extremities in 20 the header 44 with the interior of which they communicate, through openings which are here four in number and indicated by the reference character 45, Fig. 2. 46 is a lock 25 nut used to secure the fitting 32 to the connection 30, and 47 is a similar nut locking the header 44 to the plate *k* with the passage on the interior thereof communicating with the outlet passage 48, the latter being connected by the valve fitting 49 with pipe 50 30 leading to valved fitting 51 communicating with the interior of the liquid reservoir or receiver tank *g*. The lock nuts 46 and 47 produce gas tight joints between their respective fittings by binding upon gaskets of suitable packing material, as indicated in 35 Fig. 2.

The design of the machine is such that 40 cooling water from any desired source as a water works system will be taken through intake pipe 52 through the pressure operated switch control *n* and control valve 55 into coil 53 within the liquid refrigerant receiver *g* and thence through hand operated cutoff 45 valve 56 and pipe 54 into the branch fitting 57 which communicates with the two water pipes 58 and 59 controlled by hand valves 60 and 61 respectively. The pipe 58 supplies water to the cooling chamber 62 of the 50 compressor and the pipe 59 likewise communicates with the passage 63 leading through plate *k* to the interior of the condenser chamber.

Thus it will be seen that I have arranged 55 the cooling water system so that it is not necessary to pass all of the water through either the cooling means for the compressor or the condenser, but that by means of the parallel arrangement of the system I am able by manipulating the hand control valves 60, 61 to cool the compressor chamber and the oil therein in relation to the refrigerant in the condenser just as may be desired and found necessary to prevent the condensation of refrigerants in the oil. Water

from the cooling chamber 62 of the compressor will pass to the sewer pipe 64 and the cooling water from the condenser chamber will leave the chamber around the coils 36 near the top thereof so that the hot water 70 will be taken and will pass downwardly through the vertical tube 65 to a manifold or chamber 66 arranged to surround the vertical intake pipe 28 for the refrigerant at the center of the condenser chamber. The water 75 passes from this chamber through an opening at the bottom indicated by reference character 67 and thence through connecting pipe 68 to the aforesaid water discharge pipe 64. 69 is a valve controlled discharge pipe 80 for draining the water system preferably placed at the lowest point in water jacket cast integral with base *a*.

In water cooled refrigerating machines it has heretofore been common to circulate the 85 cooling water through relatively small coils in the condenser chamber with the refrigerant around the coils. In many localities where available water for cooling such devices contains impurities such as sand, alkali, and other sediments, such systems require frequent cleaning with the result that it is necessary to remove the refrigerant from the system before the apparatus may be cleaned. 90 Refrigerants such as sulphur dioxide (SO_2) are very difficult, if not impossible for any but the most skillful workmen to handle, and it is highly desirable, and one of the important features of the invention, to provide a construction of condenser in which 95 the water cooling system may be accessible and thoroughly cleaned without disturbing the system containing the refrigerant. It will be seen that I have provided such a construction, for the wall or cover *d* of the condenser may, after the water is drained from the system be detached by removing the cap nut 40 and lock nut 39 together with suitable machine screws as indicated at 100 70 and 71 so that the condenser coil will 105 be completely accessible. The pipe 50 connecting the condenser with the cooling reservoir and the expansion coil through the expansion valve, is preferably provided with a pressure gauge as indicated by reference 110 character 72, and for convenience in removing for adjusting or cleaning hand operated valves 73 and 74 will be located on each side of the expansion valve.

When the machine is properly installed 120 with the expansion coil *e* on the interior of what is commonly termed the ice chamber of a refrigerator, the coil being preferably immersed in a brine tank to stabilize the temperature of same and prevent too rapid 125 changes, and when the water intake 52 is connected with a suitable source of water supply as the waterworks system or pressure tank, with the water discharge pipe 64 connected with the sewer or other suitable 130

means for venting the cooling water and when the automatic electrical control system is connected with a suitable source for current supply as indicated by the diagrammatic arrangement of the parts in Fig. 1, the apparatus will be in condition for continuous automatic operation, it being of course understood that the refrigerating system is provided with a suitable supply of low pressure refrigerant as sulphur dioxide (SO_2), which will be introduced through the valve 75, which will also serve as a recharging valve should it be desirable at any time after the machine is in operation to add additional refrigerant. When the valve 75 is opened, the refrigerant, being ordinarily commercially contained in a closed container under pressure, will be allowed to pass into the refrigerating system on the compressor side of the check valve 21, through the compressor, and above the space in the oil level therein and into the various parts of the refrigerating system in the compressor and condenser chambers, any air therein being allowed to escape through the air needle valve 34, which may be temporarily opened for this purpose. Thence the refrigerant will be allowed to pass through pipe 50 into the liquid reservoir or receiver g and finally to the expansion valve where it will be passed under the control of the latter into the expansion coil e .

In the following description of the operation of the machine, reference being made particularly to the diagrammatic showing in Fig. 1, it should be noted that for convenience the electrical and other parts of the control apparatus are illustrated in Fig. 1 only in a diagrammatic manner and that the switching mechanism is shown correct in Figs. 5 and 6, and hereinafter described.

Current through the feed lines 76, 77 and 78 through the fuses 79, 80 and 81 will enter the system, the lines 76 and 77 being wired to the contacts 100 and 101 of the pressure operated switch n and passing thence through switches 104, 105 and contacts 102, 103 to the two knife switch arms 82 and 83 which are in substantially rigid connection with the pivoted walking beam 84 carrying at its extremities the cores 106, 107 of the solenoids 85 and 86. In the diagrammatic drawing of Fig. 1 it will be noted that for convenience the knife switch arms 82 and 83 are shown connected to a supplementary walking beam oscillatable with the walking beam 84. This is shown in the diagrammatic drawing only for the purpose of illustrating the mode of operation of the parts, the preferred design of this switching mechanism being illustrated in correct detail in Figs. 5 and 6. Connected with the walking beam and with the knife switch arms 82, 83 is the depending arm 87 varying at its extremity gear segment 88 meshing with the gear segment 108 on water valve 55. In the position of the various parts of the valve controlled switching mechanism of Figs. 1 and 6 the parts are shown in condition with the water control valve 55 closed and the pressure operated switch n held in closed position by the water pressure in the main 52 so that the current supply lines 76, 77 are closed at this point which is the normal condition of switch n . The reference character 89 indicates a temperature operated switching device or thermostat of a conventional form, the temperature operated member of which is indicated by reference character 90 and is connected with the terminal 91 of line 91 and adapted to alternately close upon the terminals of lines 92, 93 respectively, which latter are connected with the windings of the solenoids 85 and 86, the same being wired to switch contacts adapted for engagement with knife switch arm 82, the contact associated with solenoid 85 and with the knife switch arm 82 being also connected by line 94 with the motor b . Line 95 is connected with a terminal also adapted to be engaged by knife switch arm 82 and leads to the coil of the solenoid 86. Knife switch arm 83 is adapted to engage at the limit of its movement in one direction with a switch contact to which the second feed line 96 is connected and leading direct to the motor b . It will be understood that the wiring herein shown is of the ordinarily type designed for use with a three phase alternating current system, 94 and 96 being the feed lines completing the circuit independent of line 78, which does not pass through the switching mechanism. If desired to use direct current or single phase alternating current line 78 will be omitted. For this reason it will be noted that the pressure operated switching device n is only inserted in the lines 76, 77 which feed the motor lines 94 and 96, so that when both these lines are simultaneously broken no current may enter the motor. It is the function of the switching mechanism by means of the solenoids 85, 86 to cut in or cut out the current to the motor b under the control of the thermostat. The pressure operated switching mechanism n functions whenever the water pressure in the cooling system is not sufficient to properly feed the system. In such case the switch n opens the feed lines 76, 77. It will be apparent that the pressure operated switch n is for safety purposes because the compressor and condenser mechanisms depend upon the water for proper cooling and in the event of the failure of the water supply the heat generated within the compressor and condenser might injuriously effect or burn up the parts. The thermostatically operated switching mechanism 89 will be adjustable in the ordinary manner of such devices and will preferably

be located within the cooling or storage compartment of the refrigerator and it will consequently be operated to one of two positions whenever a certain predetermined temperature is passed in either direction. For example, if it be desired to maintain a temperature of forty-five degrees Fahr. within the cooling compartment of the refrigerator the thermostat will be set so that the variable member 90 thereof will make contact with line 93 at a temperature of say 46 degrees Fahr., whereas it will make contact with line 92 at a temperature of say 44 degrees Fahr. The variation in the temperature at which the thermostat will operate will depend on the type of thermostat used and the adjustment of same. Assuming that the apparatus is in working condition and the temperature around thermostat 46 degrees Fahr. or above, the variable member 90 of the thermostat will close the circuit between lines 91 and 93, the circuit being from power source through line 77, water pressure operated switch *n*, line 99, line 91, thermostat 89, line 93, solenoid 86, line 95, knife switch arm 82, line 97 to switch *n* and line 76 to power source. The closing of the above described circuit will energize solenoid 86 attracting and pulling down core 107 and operating knife switch arms 82, 83, the former thereby disconnecting line 97 from line 95 and connecting line 97 to solenoid winding 85, and the latter thereby connecting line 99 to line 96. Under this condition of the switch mechanism the motor *b* starts, receiving power through line 78 directly; also from line 77 through pressure operated switch *n*, line 99, knife switch arm 83, and line 96; also from line 76 through pressure operated switch *n*, line 97, knife switch arm 82, and line 94. It should be noted that the movement of knife switch arm 82 disconnects line 95 from 97 thus cutting off power from solenoid 86 as soon as this solenoid has functioned. It should also be noted that the depression of solenoid core 107 will shift segment arm 87 and valve segment gear 108 opening water control valve 55 and supplying cooling water to the entire cooling system. The starting of the motor and compressor under these conditions will result in the circulation of the refrigerant through the system, and consequent cooling of the expansion coil, which condition will obtain until the temperature of air surrounding the thermostat is lowered to say, approximately 44 degrees Fahr. when movable contact 90 of the thermostat will close circuit between lines 91 and 92 causing flow of current in solenoid 85 through line 77, pressure operated switch *n*, line 99, line 91, thermostat 89, line 92, solenoid winding 85, knife switch arm 82, line 97, pressure operated switch *n*, and line 76 to source, resulting in attracting and pull-

ing down solenoid core 106, shifting knife switch arms 82, 83 back to the positions shown, full lines, Fig. 1, resulting in breaking circuit between lines 96 and 99 and also breaking the circuit between lines 94 and 97 leaving line 78 connecting motor directly with power source and line 77 connecting motor with power source through the high resistance winding of solenoid 85, under which conditions the motor will stop and remain at rest until thermostat switch is again affected by a rise in temperature. It should also be noted that the depression of solenoid core 106 will close water control valve 55 preventing waste of water when not needed in cooling compressor and condenser. 75 80

Reference will now be made to the preferred form of the water pressure controlled electrical system of Figs. 5 and 6 shown only in diagrammatic form in Fig. 1 as previously referred to in the described operation of the machine. While this water pressure operated switching mechanism has been designated generally by reference character *n* it will be seen that there is a specially formed pipe fitting of irregular shape as indicated by reference character 110 inserted between the sections 52 and 53 of the water supply inlet pipe and that the passageway through this fitting is under the control of the before described control valve 55 operated by gear segment 108. Within the housing formed in the passageway through fitting 110 and on the water supply or inlet side of control valve 55, I mount a collapsible chamber so that a portion of the collapsible walls of said chamber will be exposed to the pressure of the water within the fitting on the inlet side of the control valve. Such a chamber may be of cylindrical shape, formed for example, from some suitable spun ductile metal as brass or copper with one end formed integrally with the cylindrical walls thereof as indicated by reference character 111, the said end portion having connected thereto a part 112 provided with a screw threaded socket (Fig. 6) adapted to take the threaded extremity of a shaft or pin 113 carrying at its upper end a cross head 114 to which will be attached but insulated therefrom the two switch members 104, 105 previously referred to, and one of which is shown in Fig. 6, being adapted when closed upon the line terminal contacts 101 to 103 inclusive to close the respective circuits through said contacts, as already described. The cylindrical walls of the chamber 111 will be given a sinuous form in section, as indicated at 115 to render the same collapsible upon the application of fluid pressure within the passage of the fitting and the outer end of the chamber may be closed by suitable plate as indicated at 116 through which the switch operating shaft 113 will loosely pass, there being a 90 95 100 105 110 115 120 125 130

coil spring 117 adapted to exert a normal expansive effect between plate 116 and the bottom of the chamber, the said spring being positioned around the shaft 113 and may be conveniently seated at its end opposite the plate 116 upon the part 112, whereby to depress the switch members and break the described circuit contacts whenever the pressure of the water on the supply side of the control valve 55 falls below a predetermined pressure. The collapsible chamber 111 for operating the switch mechanism may conveniently be secured to the substantially circular fitting 118, screw threaded in the threaded opening as indicated on the top of fitting 110 and having a clamping circular plate 119 attached thereto, there being circular recesses formed, as illustrated, in one or both of said parts 118, 119 to receive the flanged peripheral edge of the collapsible chamber member and the periphery of plate 116.

The line terminals 100 to 103 inclusive are preferably secured to the underside of base plate 120 which for the protection of the solenoids operating parts of the switch mechanism connected therewith may be provided with the suitable cover 121 and with a vertical branch preferably connected integrally therewith as indicated at 122, serving as a support for the three fuses 79 to 81 in the main current supply lines 76 to 78 inclusive as heretofore referred to and shown in the diagrammatic portions of Fig. 1. 123, 124 and 125 are suitable binding posts in feed lines 76 to 78 respectively. The fuses 79 and 80 have suitable electrical connections through their respective binding posts with binding posts of contacts 100, 101, and the circuit in line 78 is continued through fuse 81 and binding post 126 to the motor as shown in the diagrammatic illustration Fig. 1. In the detail views Figs. 5 and 6 no attempt is made to illustrate the circuit connections between switch contacts, solenoids and motor, as shown in Fig. 1, but the operation of the switching mechanism will be understood from the diagrammatic arrangement of the corresponding parts in Fig. 1. It will be observed that knife switch arms 82 and 83 engage the respective switch sockets 94^a, 95^a and 96^a in lines 94 to 96 inclusive, as described, and it will be borne in mind that the switch arms 82 and 83 which will be suitably connected to be operated by the oscillation of the walking beam 84 will be insulated therefrom and from the supporting brackets 127, 128 and that these knife switch arms 82, 83 will have connected in circuit therewith suitable flexible wires to provide the electrical connections heretofore described and as illustrated in Fig. 1. No attempt is made to enter into the details of the mechanical connection of knife switch arms 82, 83 with the oscillating beam 84 carry-

ing the magnet cores, as the same forms no part of the present invention, and theoretically the switching device described would be operative if the knife switch arms were substantially rigidly connected to oscillate with beam 84 and with the pivotal shaft as indicated by reference character 129, by which the same is supported in said brackets 127, 128. However, in order to prevent arcing between the switch arms and their respective contacts, I prefer to use suitable means such as are common and well known for giving a quick throw to the knife switch arms 82 and 83 independently of the movement of walking beam 84 so that the switch arms will not operate with the oscillations of the walking beam 84, but may be operated with a quick snap from each of their two position to the opposite position by suitable spring or elastic means under the control of the magnetically operated beam 84, and upon each separate oscillation thereof.

Reference has been made to the distortion of the compressor casing *c* of the diagrammatic Fig. 1 and to show therein a vertical section through water jacket 62 and water supply and vent connections the same is distorted almost ninety degrees as will be apparent from the correct views in section in Figs. 2 and 3, and from which it will be seen that the inner wall of the jacket is provided with fins 150, this increasing the cooling surface exposed to the liquid within the compressor.

In Fig. 2 certain details of the pump casting *j* are shown including the packing and bearing for drive shaft 10 which is more particularly described in a separate application on the pump per se.

In the form of the base *a* of Fig. 1 an extension of the water cooling jacket 62 of the compressor is formed integrally within the casing. In Fig. 2 I show a modified construction in which the base plate as indicated by reference character *a'* is of a much simpler design, having no provision for the water jacket therein but having a plate 140 approximately circular in cross section to correspond with the circular lower flanged portion *j'* of the compressor casing, and as in the form of the compressor casing *j* shown in Fig. 1 the bottom of the casing will be constructed with an opening therein almost as large as the internal diameter of the casing with an opening 142 therein adapted to have attached thereto a suitable closure as an ordinary try-cock, not shown, for draining the interior of the compressor casing. The plate 140 will be provided with duct 142' extending radially from the periphery thereof at the outside radius of the compressor casing and closed by a suitable drain valve connection indicated by reference character 143 which may be opened

when the machine is not in operation for the purpose of draining cooling fluid from the system, this normally being the lowest point in the cooling system. The fitting 143 will preferably be constructed in the form of a two way cock so that in one position the drain spout 144 thereof may be closed with a passageway through the cock connecting with the water supply pipe 58 for feeding the cooling jacket of the compressor chamber. Also when the valve 143 is closed to prevent the circulation of water from the pipe 58 into the jacket passage 142' the valve should open for draining the system through the discharge outlet. The upper surface of plate 140 surrounding the discharge of duct 142' will be provided with concentric heat conducting fins as indicated at 145 and the opening in the bottom of the condenser chamber *j* will be closed by a specially constructed plate 146 attached thereto by suitable machine screws, as indicated in Fig. 2, the plate 146 being provided with heat conducting fins on both its upper and lower surfaces, as indicated by reference characters 147 and 148. This modified construction for the base plate and the compressor casting and jacket connections therefor not only results in a considerable saving of manufacturing costs due to the difficulty of properly casting a supporting base plate of the type indicated by reference character *a* but the various portions being detachable the interior portions of the water jacket are rendered easily accessible for cleaning.

Reference has heretofore been made to the test cocks 15 and 16 for determining the liquid level in the compression chamber. In Fig. 4 I show the preferred form of such device consisting of a screw threaded plug *r* adapted for insertion in both of the openings 13 and 14 of the compressor casing, said plug being provided with a head polygonal in cross section and having on the exterior thereof a recessed portion *s* adapted to receive the polygonal head of a screw plug *t* threaded in an opening *v*, which extends longitudinally of plug *r* terminating near its extremity opposite its head portion and on the interior of the chamber *c* in a contracted duct indicated by reference character *x*, this construction forming a seat for the pointed inner end *y* of the screw plug *t* so that the duct or orifice *x* may be kept normally closed but opened whenever desired by the use of a tool applied to the head of plug *t* which may be adjusted to uncover the orifice *x* and permit discharge of liquid from the interior of the compressor chamber into the plug opening *v*, thence through duct *z* through the wall of plug *r* to atmosphere.

160 is a baffle plate adjacent pump discharge pipe 25 adapted to retard oil circulation in the compressor chamber and tending to prevent or lessen any intermingling of

refrigerant that might be intermingled with liquid in the bottom of the compressor chamber with fresh supply fed from the pump.

I claim:

1. In an apparatus using cyclic expansion and compression of a refrigerant, the combination of a compressor having a chamber adapted to contain compressed refrigerant, means for driving the compressor including an electric circuit and a switch therein, a second chamber adapted to receive refrigerant under pressure, conduit means for circulating water to cool one of said chambers said conduit means including a water valve, a common control means for controlling the operation of said switch and said water valve, and means responsive to the pressure of the cooling water for rendering said control means inoperative.

2. In an apparatus of the character described, the combination of a compressor, a condenser, an expansion chamber, means connecting said compressor, condenser and expansion chamber in a closed refrigerating circuit, means for driving the compressor including an electric circuit and a switch therein, conduit means for conducting cooling water to the condenser, said conduit means including a water valve for controlling the circulation of water, a common control means for controlling the operation of said switch and said water valve, and means responsive to the pressure of the cooling water for preventing the operation of the control means.

3. In an apparatus of the character described, the combination of a compressor, a condenser, an expansion chamber, means connecting said compressor, condenser and expansion chamber in a closed refrigerating circuit, means for driving the compressor including an electric circuit and a switch therein, conduit means for conducting cooling water to the condenser, said conduit means including a water valve for controlling the circulation of water, a common means mechanically connected with said switch and said valve for operating the switch and valve, and means responsive to the pressure of the cooling water for rendering said common means inoperative.

4. In an apparatus of the character described, the combination of a compressor, a condenser, an expansion chamber, means connecting said compressor, condenser and expansion chamber in a closed refrigerating circuit, means for driving the compressor including an electric circuit and a switch therein, conduit means for conducting cooling water to the condenser, said conduit means including a water valve for controlling the circulation of water, a common control means for controlling the operation of said switch and said water valve, and means

operative after the circuit has been closed and the water valve has been opened to automatically open the circuit upon the pressure of the cooling water falling below a predetermined limit while permitting the water valve to remain open.

5. In a refrigerating apparatus, the combination with a compressor chamber, a compressor therein, a condenser chamber comprising a refrigerant-cooling coil therein, a common wall sealing the compressor chamber and the condenser chamber, water supply means, ports and passages entirely in said common wall for conducting the cooling water and the refrigerant into and out of the condenser.

6. In a refrigerating apparatus, the combination with a compressor chamber, a compressor therein, a condenser chamber comprising a refrigerant-cooling coil therein, a common wall sealing the compressor chamber and the condenser chamber, water supply means, ports and passages entirely in said common wall for conducting the cooling water and the refrigerant into and out of the condenser, there being but a single passage extending through the common wall connecting the compressor chamber with the condenser chamber.

30 7. In a refrigerating apparatus, the combination with a condenser and an expansion coil, of a compressor casing, a compressor

adapted to discharge refrigerant into said casing, cooling fins on the interior wall of said casing, and means for conducting a cooling medium into contact with the outer surface of the wall of said casing whereby to cool said fins and the contents of said casing.

8. In a refrigerating apparatus, the combination with a condenser and an expansion coil, of a compressor casing, a compressor adapted to discharge refrigerant into said casing, cooling fins on the interior wall of said casing at two or more sides thereof, and means for conducting a cooling medium into contact with the outer surface of the wall of said casing whereby to cool said fins and the contents of said casing.

9. In a refrigerating apparatus, the combination with a condenser and an expansion coil, of a compressor casing, a compressor adapted to discharge refrigerant into said casing, cooling fins on the interior of the bottom wall of said casing, and means for conducting a cooling medium into contact with the outer surface of the wall of said casing whereby to cool said fins and the contents of said casing.

In testimony whereof I have signed my name to this specification on this 24th day of October A. D. 1919.

CHARLES L. McCUEN.
